UNITED STATES PATENT OFFICE

140,709

DESIGN FOR A DOLL OR SIMILAR ARTICLE

Allen L. Grammer, Montclair, N. J.

Application June 30, 1944, Serial No. 114,263

Term of patent 14 years

(Cl. D34—4)

To all whom it may concern:

Be it known that Allen L. Grammer, a citizen of the United States and resident of the city of Montclair, county of Essex, State of New Jersey, has invented a new, original, and ornamental Design for Doll or Similar Article, of which the following is a specification, reference being had to the accompanying drawing forming part thereof, in which

Fig. 1 is a front view and Fig. 2 is a rear view of the doll embodying my new design.

I claim:

The ornamental design for a doll or similar article, substantially as shown.

ALLEN L. GRAMMER.
